UNITED STATES PATENT OFFICE.

JOSEPH BARR, OF ALLENTOWN, AND WILLIAM J. MONTZ, OF ORMROD, PENNSYLVANIA.

GRINDING-MILL.

No. 893,893.

Specification of Letters Patent.

Patented July 21, 1908.

Application filed December 14, 1907. Serial No. 406,459.

To all whom it may concern:

Be it known that we, JOSEPH BARR, of Allentown, and WILLIAM J. MONTZ, of Ormrod, in the county of Lehigh and State of Pennsylvania, citizens of the United States, have made certain new and useful Inventions Relating to Grinding-Mills, of which the following is a specification, taken in connection with the accompanying drawing, 10 which forms part of the same.

This invention relates to grinding mills, and relates especially to the trunnion construction of centrifugal Griffin mills.

In the accompanying drawings showing an 15 illustrative embodiment of this invention, and in which the same reference numeral refers to similar parts in the several figures, Figure 1 is a vertical central section through a grinding mill. Fig. 2 is a detail transverse 20 section of the trunnion and adjacent pulley construction; and Fig. 3 is a perspective view of the trunnion member.

In the illustrative embodiment of this invention shown in the drawings, the grinding 25 mill comprises the heavy base 1 formed with the grinding pan 2 and carrying the heavy frame 3. The ring die 5 may be firmly secured in position by the wedging action of the adjacent part of the casing 6 which as indicated may be screwed down upon it. This 30 casing may be provided with the feed chute 7 and the upwardly extending casing cone 8. The upper part of the frame which may be formed in two parts bolted together by the 35 heavy bolts 26, may carry the bushing 18 in which the collar 19 is adjustably mounted, as by the indicated screw connection between the parts. The sleeve 12 may, if desired, be provided with the sleeve flange 11 having a 40 threaded connection with the collar and firmly secured in adjusted position thereon by the stay bolts 20 so as to rigidly support this bearing sleeve from the frame. The pulley 16 may be formed with an integral hub 45 30 having a conical inner face to coöperate with the sleeve and adapted to rest at its lower end on the bearing rings 35. This pulley as indicated may be formed with the rim 15 and the head 23 inclosing the trunnion member and being held in alinement by the stud 25 which has a bearing therein and which is rigidly supported by the yoke 24 secured to the frame.

The roll 4 coöperating with the die 5 may 55 be rigidly secured upon the roll-shaft 9 provided with the fans 10. The roll-shaft may

be rigidly secured to the trunnion member by having a conical portion passing through the same and engaged by the bolt 21 so that the roll is properly supported within the die. 60 As indicated, the trunnion ball 13 may rest upon the socket 36 and be properly maintained in coöperation therewith by a pressure ring 38 resting upon the ball and yieldingly pressed against the same by the pressure 65 spring 22, although it is, of course, understood that the grinding mill to which this particular trunnion construction is applied need not be formed exactly as described.

The trunnion member may be formed with 70 the reduced necks 32 projecting laterally outward on opposite sides of the ball and carrying the enlarged heads 14 for engagement with the driving faces of the pulley. As indicated in Fig. 3, the heads may have a substantially uniform cross-section and be eccentrically located with respect to the axis of the necks so as to have their projecting driving faces 28 on opposite sides of this axis. These heads are preferably formed with a 80 somewhat flattened curved driving face 28 to coöperate with the steel spline 17 forming the coöperating driving face of the pulley. The other part of the head is preferably eccentric with the neck and substantially tangent to the 85 surface thereof on the side opposite the driving face of the head. In this way the head is provided with ample bearing surface and can readily slide vertically up and down the driving face of the pulley as well as turn 90 against it, both these motions taking place in the operation of the mill. By forming the head 14 of the trunnion member eccentric with respect to the neck 32, a large amount of wear can take place without requiring the 95 renewal of the trunnion member and the wear can be readily taken up from time to time by inserting a thicker spline 17 so as to bring the driving face of the pulley sufficiently close to the opposing wall 37 of the driving slot in the 100 pulley. As the pulley slot may be sufficiently filled with oil so that the trunnion heads run in practically an oil bath the wear is quite small and furthermore, as has been demonstrated, these integral heads give a 105 much more reliable and definite driving action and are less subject to breakage than where separate loose parts are employed.

Having described this invention in connection with an illustrative embodiment thereof, to the details of which disclosure the invention is not, of course, to be limited, what

is claimed as new and what is desired to be secured by Letters Patent is set forth in the appended claims.

1. In grinding mills, a pulley having a bearing socket and driving faces, a roll-shaft and connected trunnion member provided with a spherical portion to coöperate with said bearing socket, said trunnion member having reduced necks extending laterally outward from said spherical portion in opposite directions and enlarged integral eccentric heads on said necks, said heads being of substantially uniform cross-section and having curved flattened driving faces on the sides away from the axis of said necks to engage the driving faces of said pulley.
2. In grinding mills, a pulley having a bearing socket and driving faces, a roll shaft and connected trunnion member provided with a bearing portion to coöperate with said bearing socket, said trunnion member having necks extending laterally outward

from said bearing portion in opposite directions and integral eccentric heads on said necks and having curved flattened driving faces on the sides away from the axis of said necks to engage the driving faces of said pulley.

3. In grinding mills, a pulley provided with driving faces, a trunnion member to be secured to a roll shaft and having a bearing portion, a bearing socket with which said bearing portion coöperates, said trunnion member being provided with necks having heads rigid with said bearing portion and extending laterally outward therefrom in opposite directions, said heads having curved driving faces to engage the driving faces of said pulley.
